WHEEL WEIGHT TOOL

Paul W. Nethercot, 108 Fay St., Hutchinson, Kans.

Filed Apr. 14, 1961, Ser. No. 64,748

Term of patent 3½ years

(Cl. D54—13)

FIGURE 1 is a front elevational view of a wheel weight tool showing my new design;

FIGURE 2 is an elevational view taken from the right side of FIGURE 1 thereof;

FIGURE 3 is a rear elevational view thereof;

FIGURE 4 is a sectional view taken along the line of 4—4 of FIGURE 3 thereof; and

FIGURE 5 is a sectional view taken along the line 5—5 of FIGURE 3.

I claim:

The ornamental design for a wheel weight tool, as shown.
